UNITED STATES PATENT OFFICE.

GLENN MORE, OF JAMESTOWN, NEW YORK, ASSIGNOR TO BLACKSTONE MANUFACTURING COMPANY, OF JAMESTOWN, NEW YORK, A CORPORATION OF NEW YORK.

GEARING FOR WASHING MACHINES.

Application filed February 7, 1921. Serial No. 443,215.

To all whom it may concern:

Be it known that I, GLENN MORE, a citizen of the United States, residing at Jamestown, in the county of Chautauqua and State of New York, have invented certain new and useful Improvements in Gearing for Washing Machines, of which the following is a specification, reference being had to the accompanying drawings, and to the reference characters marked thereon, which form a part of this specification.

This invention relates to gearing for washing machines, and more particularly to that type of cylinder washing machines, wherein the cylinder is rotated about its longitudinal axis, alternately in one direction and then in the other.

The object of the invention is to provide a gearing which will have certain parts that may be set in motion by the application of power from a motor or other source of supply, but which will not necessarily at the same time actuate either the cylinder of the washing machine or the wringer rolls of a wringer which may be attached to the washing machine.

Another object of the invention is to provide means accessible to the operator of the machine, whereby certain operative parts may be connected together so as to throw the cylinder into operative connection with the moving parts and thus rotate the cylinder.

Another object of the invention is to provide means for disconnecting the cylinder rotating means from the constantly rotating mechanism, thus stopping the cylinder from rotation when it is desired to operate only the wringer mechanism.

Another object of the invention is to provide a seat or means for attachment of a wringer mechanism, to the washing machine, and to place operative gearing in juxtaposition thereto, adapted to engage the wringer mechanism to operate the latter.

The invention consists in the various devices and combinations of devices herein-after illustrated, described and claimed.

In that form of machine in which I have chosen to exemplify my invention, in the accompanying drawings, it will be observed that the ratio of the gearing is such that the cylinder will be given a complete rotation in one direction, then reversed and given a complete rotation in the other direction.

In the drawings:

Fig. 1 is a side elevation of a washing machine of the cylinder type, embodying my invention,—part of the frame being broken away.

Fig. 2 is a side view, enlarged, of a part of the operating mechanism shown in one position.

Fig. 3 is a similar view of the same mechanism, shown in a different position.

Fig. 4 is a vertical section through the frame of the machine, showing the operating mechanism in end elevation.

Fig. 5 is a detail showing the rocking trip arm in side elevation looking at the parts in the plane indicated by the dotted line 5—5 of Fig. 2.

Fig. 6 is a transverse sectional view of a pivoted detent, the section being taken upon the plane of the dotted line 6—6 of Fig. 2, looking in the direction indicated by the arrow.

Fig. 7 is a similar view, showing the same parts with the detent raised.

Fig. 8 is an end view of the detent in the position shown in Fig. 6.

Fig. 9 is an end view of the detent in the raised position shown in Fig. 7, and engaged with a crank arm.

Fig. 10 is a side elevation of a crank arm adapted for engagement with the raised detent.

Fig. 11 is an inside face view of the crank arm looking at it in a direction away from the partition wall.

Fig. 12 is a sectional detail view, showing the mounting of the crank and gear wheel the section being taken in the plane indicated by the dotted line 12—12 of Fig. 2.

Referring now to said drawings, A indicates as a whole, the washing machine comprising an outer case having side walls *a*, *a*, end walls *b*, *b*, a top *c*, provided with a hinged lid *d*, and an interior partition wall *e*. Between the partition wall *e* and one end wall *b* is the cylinder chamber *B*, in which is located a suitable cylinder *C*, adapted to contain the clothes to be washed. Between the partition wall *e* and the front wall *b* is what I call an operating chamber *D*, which contains the operating mechanism, driven by any suitable source of motive power, as for example an electric motor *E*.

F is an operating shaft in the chamber *D*, and is suitably connected by mechanism

about to be described, so as to cause the rotation of the cylinder C. G is a plate or casting located in the chamber D and suitably secured to the partition wall e and to the other parts of the machine by bolts or otherwise. On this plate G is mounted the operative mechanism.

The end wall b is provided interiorly with a suitable bearing plate 1, adapted for operative engagement with a pin plate 2 located upon the end of the cylinder C. A recessed bearing plate 3 is located on the opposite end of the cylinder C and adapted to receive the inner end of the operating shaft F, and is suitably connected to the shaft F as by a spline or otherwise, so as to be rotated with said shaft. 4 is a grooved pulley or sheave mounted on the shaft of the motor E, by which power is communicated by a belt 5 to a larger belt sheave 6, loosely mounted upon the shaft F. Integral with the sheave 6 and therefore also loosely rotatable upon the shaft F, is a driving pinion 7. 8 is a suitable opening or aperture through the partition wall e and 9 is a stuffing box or gland located in said opening and surrounding the shaft F. 10 is an operating, beveled pinion keyed or otherwise secured to the shaft F. 11 is a gear wheel mounted upon the shaft 12, having its teeth adapted to intermesh with the pinion 7.

The shaft 12 is located in suitable bearings 13, upon the casting or plate G, with its longitudinal axis parallel to the axis of the shaft F. 14 is a spur pinion on the shaft 12. 15 is a spur gear upon a shaft 16, the teeth of which gear 15 mesh with the teeth of the pinion 14. The shaft 16 is suitably mounted on the plate or casting G. 17 is a small spur gear, rotatably mounted in the upper part of the plate G so that its teeth will mesh with the gear 15.

H is a crank on the shaft 16. As shown, however, (Fig. 12) the crank is immediately mounted upon an extended hub of the gear 15, the latter being mounted upon the shaft 16, since this arrangement gives a better bearing for the gear 15 and also for the crank H.

I and J are links. The links I are loosely mounted at one end upon the shaft F. The link J is pivotally connected at 18 to the crank H and pivotally connected at 19 to the movable ends of the links I. 20 is a segmental rack, the teeth of which are adapted to mesh with the pinion 10. It is this segmental rack that carries the laterally extended pins 19, one on each side, and upon which the ends of the links I, I, are loosely mounted.

Upon the face of the spur gear 15 is located a pivoted arm or detent 21, provided at its free end with a tapered or angular face 22. The inside rim of the gear 15 at the place where the detent 21 is located, is

provided with a double cam rib 23, against which a friction ball 24 will operate. In a suitable recess in the detent 21, I locate a spring 25 which tends normally to press the friction ball 24 outwardly against the cam rib 23 and to frictionally hold the detent 21 either in its raised position, above the point of the rib 23, or in its lower position below the point of the rib 23.

The crank H is L-shaped as shown, by the extension 26, and is provided with an outwardly extending lug 27. On the under side of the extension 26 is a transverse recess 28 of a width adapted to receive the detent ball 24. The forward end of the under side of the extension 26 is tapered as shown at 29.

30 is a rocking trip arm, pivotally mounted at 31, and provided with cam surfaces 32, 33. The cam surface 32 is adapted to engage the outer end of the detent 21, when in the path of said detent 21, and thus raises the detent to its upper position, shown in Fig. 7. The cam surface 33 may be called the disengaging cam, it being adapted to bear against the inclined surface 22, when brought into the path of the detent 21 and thus depress the detent 21 to its lower position.

34 is an operating or trip handle pivoted at 35 and provided with an engaging finger 36, the latter being adapted to enter a suitable recess or socket 37 in the forward end of the trip arm 30. The detent 21 is flanked on each side by brackets 38, which not only provide for the pivotal bolt 39 of the detent 21, but also afford much strength against any lateral pressure brought to bear upon the detent 21.

40, 40 are bearing surfaces upon which a suitable removable wringer mechanism, not shown in the drawings, may rest, and be connected to the washing machine A so that the operative gearing of said wringer mechanism may engage with and be driven from the pinion 17.

To drive the cylinder C from the motor, power is transmitted by the belt 5 to the sheave 6, through the pinion and gears 7, 11, to the shaft 12, and through the pinion 14 to the gear 15. The handle 34 is moved into position shown in Fig. 2, so that the engaging cam 32 will lie vertically over the rim of the gear 15 and thus be in the path of the detent 21. This detent 21 being secured to the gear 15, rotates with it constantly and is brought to its raised position when lifted by the cam 32. The crank H being loosely mounted, of course is not moving at this time, but as soon as the raised detent 21 in the rotation of the gear 15, comes into position beneath the extension 26 of the crank, the detent engages with the walls of the recess 28. The detent and the crank H are thus locked to-

gether and the crank H is rotated about the shaft 16 and will continue to be rotated until the position of the arm 30 is reversed.

When it is desired to break this contact and unlock the crank arm H so that it will not rotate with the wheel 15, the handle 34 is grasped and the arm 30 is moved from the position shown in Fig. 2 into the position shown in Fig. 3, which brings the releasing cam surface 33 into the path of the detent 21. When in the rotation of the wheel 15, the detent 21 is thus brought into juxtaposition, the cam surface 22 and the releasing cam surface 33 contact, with the result that the forward end of the detent 21 is depressed and contact between the detent 21 and the extension 26 of the crank H is broken. Thereupon the wheel 15 will continue its rotation but movement of the crank H will cease.

When the crank H is connected through the detent 21 with the wheel 15, and partakes of the rotation of the wheel, the segmental rack 20 is actuated, through this connection, with the crank H, through the links J and I, the segment being actuated or rocked first in one direction and then in the other. This alternate reciprocation results in the rotation of the pinion 10 one complete revolution in each direction. That is to say, the pinion 10 is rotated a complete revolution to the right and then is reversed and rotated a complete revolution in the opposite direction. This alternate, rotary motion of the pinion 10 is communicated, of course, to the cylinder drive shaft F, with the result that the cylinder C within the compartment B is likewise given a complete rotary movement or rotation in one direction and then reversed and given a complete rotation in the opposite direction, producing the desired tumbling of the clothes within the wash water, and cleansing the clothes in a familiar manner.

It will be observed that the relation of the teeth on the segmental rack 20 and the number of teeth on the pinion 10 is such as to produce but a single rotation of the shaft F before reversal. But, it will be obvious that a greater or less rotation of the shaft F before reversal may be obtained by changing the ratio of the teeth. This is so obviously within the skill of the mechanic, that illustration and further explanation are not necessary.

Of course, the wringer driving pinion 17 is also constantly moving, being in mesh with the constantly driven gear 15; but the wringer is not in operation unless desired because all wringers have stopping and starting devices and the presumption is that when the cylinder is in operation, the wringer mechanism will be upon neutral, so that the gear 17 will be running idly and doing no harm. If, however, the posi-

tion of the wringer with relation to the washing machine is such that clothes are being passed through the wringer from one tub to another, and not from the cylinder to the wringer, then, it is obvious, that by reason of the definite rotation of the driving pinion 17, the operator may be wringing washed clothes while the machine is washing soiled garments in the cylinder C—thereby saving much time.

When it is desired to pass washed garments from the cylinder C to the wringer, obviously the rotation of the cylinder must be suspended. This is accomplished by swinging the lever 30 into position, whereby the cam 33 will throw the detent 21 into its lower position, thus unlocking the crank H and wheel 15. Thereupon the cylinder C will cease rotating although the motor E will continue in operation and power will be transmitted through the gears 7, 11, 14, 15 and 17 to the wringer mechanism. It will be noted that in the arrangement of parts above described, there is very little to get out of order and very few moving parts to be handled by the operator. For example, there will be the usual switch for turning on and off the power to the motor. There will be a handle 34 for throwing the cylinder operating gear into and out of engagement with the parts actuated from the motor. There will be on the wringer a lever throwing the mechanism that is connected with the driving gear 17 into and out of operation. If, for example, a reversing wringer mechanism is used, this third lever will have a neutral position and a position to the right and left of the neutral, into which the lever may be moved to cause the wringer rolls to turn in one direction or to reverse and turn in the opposite direction. Such wringer operating mechanism is usually located close to the point of attachment of the wringer to the machine proper, and therefore it will be noted that the handle 34 of my machine is positioned very conveniently for the use of the operator.

It will also be noted that the entire operative mechanism of my machine is mounted upon a plate or casting G and thus constitutes what may be called a self contained unit, the parts of which are easy to assemble in the shop, and which units are readily applied to the frame of the machine, as will be understood by those skilled in the art.

I claim as my invention:

1. A gearing unit comprising a rotatable shaft, a driving member rotatably and loosely mounted on said shaft, a driven member adapted for continuous rotative movement in the same direction, a second driven member fixed to said shaft and adapted for rotative movement alternately

in opposite directions, gearing means for operating said driven members, and connecting and disconnecting mechanism acting upon said gearing operating means whereby the movement of the rotatable driving unit is transmitted to continuous rotative movement of one of the driven members and is translated to alternate rotative movement of the other driven member, as desired.

2. The combination with a fixed support and a driving shaft rotatably mounted thereon, of a pinion loosely mounted upon said shaft, a pinion fixedly mounted on the 15 shaft to rotate therewith, a stub shaft mounted on the support, a spur gear revolvably mounted upon the stub shaft, gearing connecting said spur gear with the loosely mounted pinion, means for actuating the 20 latter, a crank associated with said spur gear, a pivoted toothed segment in mesh with the pinion fixed on the driving shaft, said segment being operatively connected with said crank, a shoulder on the crank, 25 a detent on the spur gear adapted to engage said shoulder, and means for controlling said detent.

3. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolvably mounted upon the stub shaft, gearing connecting said spur gear with the loosely mounted pinion, means for actuating the latter, a crank associated with said spur gear, a pivoted toothed segment in mesh with the pinion fixed on the driving shaft, 40 said segment being operatively connected with said crank, a shoulder on the crank, a detent on the spur gear adapted to engage said shoulder, a controlling arm provided with means for causing the detent 45 to engage said shoulder while the spur gear is in continuous rotation.

4. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolubly mounted upon the stub shaft, gearing connecting said spur gear with the loosely mounted pinion, means for actuating the latter, a crank associated with said spur gear, a pivoted toothed segment in mesh with the pinion fixed on the driving shaft, said segment being operatively connected with said crank, a shoulder on the crank, a detent on the spur gear adapted to engage said shoulder, a controlling arm provided with means for causing the detent to become disengaged from said shoulder while the spur gear is in continuous rotation.

5. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolvably mounted upon the stub shaft, gearing connecting said spur gear with the loosely mounted pinion, means for actuating the latter, a crank associated with said spur gear, 70 and a lever pivoted to the support and connected with the driving shaft and the means for actuating the latter, 75

latter, a crank associated with said spur gear, a pivoted toothed segment in mesh with the pinion fixed on the driving shaft, said segment being operatively connected with said crank, a shoulder on the crank, a 80 detent on the spur gear adapted to engage said shoulder, and means for controlling said detent, said controlling means including a pivoted manually operated lever having two cams the engaging surfaces of which are oppositely inclined, said cams being adapted to be alternately brought into the path of the moving detent by said lever 85 to raise or depress the latter as desired.

6. The combination with a fixed support and a driving shaft rotatably mounted thereon of a pinion loosely mounted upon

7. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolvably mounted upon the stub shaft, gearing connecting said spur gear with the loosely mounted pinion, means for actuating the latter, a crank associated with said spur gear, a pivoted toothed segment in mesh with the pinion fixed on the driving shaft, said segment being operatively connected with said crank, a shoulder on the crank, a detent on the spur gear adapted to engage said shoulder, and means for controlling said detent, said controlling means includ-

ing a pivoted manually operated lever having two cams the engaging surfaces of which are oppositely inclined, said cams being adapted to be alternately brought into the path of the moving detent by said lever to raise or depress the latter as desired, said detent being pivotally mounted upon the spur gear and provided with means cooperating with the spur gear to frictionally hold the detent in either its raised or its lowered position.

8. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolvably mounted upon the stub shaft, gearing connecting said spur gear with the loosely mounted pinion, means for actuating the latter, a crank associated with said spur gear, a pivoted toothed segment in mesh with the pinion fixed on the driving shaft, said segment being operatively connected with said crank, a shoulder on the crank, a detent on the spur gear adapted to engage said shoulder, and means for controlling said detent, said controlling means including a pivoted manually operated lever having two cams the engaging surfaces of which are oppositely inclined, said cams being adapted to be alternately brought into the path of the moving detent by said lever to raise or depress the latter as desired, said detent being pivotally mounted upon the spur gear and provided with means cooperating with the spur gear to frictionally hold the detent in either its raised or its lowered position.

9. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolvably mounted upon the stub shaft, gearing connecting said spur gear with the loosely mounted pinion, means for actuating the latter, a crank associated with said spur gear, a pivoted toothed segment in mesh with the pinion fixed on the driving shaft, said segment being operatively connected with said crank, a shoulder on the crank, a detent on the spur gear adapted to engage said shoulder, and means for controlling said detent, said controlling means including a pivoted manually operated lever having two cams the engaging surfaces of which are oppositely inclined, said cams being adapted to be alternately brought into the path of the moving detent by said lever to raise or depress the latter as desired, said detent being pivotally mounted upon the spur gear and provided with means cooperating with the spur gear to frictionally hold the detent in either its raised or its lowered position.

10. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolvably mounted upon the stub shaft, gearing connecting said spur gear with the loosely mounted pinion, means for actuating the latter, a crank associated with said spur gear, a pivoted toothed segment in mesh with the pinion fixed on the driving shaft, said segment being operatively connected with said crank, a shoulder on the crank, a detent on the spur gear adapted to engage said shoulder, and means for controlling said detent, said controlling means including a pivoted manually operated lever having two cams the engaging surfaces of which are oppositely inclined, said cams being adapted to be alternately brought into the path of the moving detent by said lever to raise or depress the latter as desired, said detent comprising a vertically movable arm horizontally pivoted to lugs on the spur wheel and frictional means mounted in the detent to cooperate with the rim of the said gear.

11. Gearing of the class described comprising in combination with a fixed support, a stub shaft mounted thereon, a rotatable driving shaft mounted therein and a shaft intermediate the latter and the stub shaft, of a driving pinion fixed on the driving shaft to rotate the same, a spur pinion loosely mounted to rotate about said driving shaft, a spur gear mounted to rotate said stub shaft, a spur gear and a pinion mounted upon the intermediate shaft and meshing respectively with the loosely mounted pinion and the spur gear, a link loosely mounted at one end upon the driving shaft, a crank loosely mounted at one end upon the stub shaft, a toothed gear segment pivotally connected to the free ends of said link and of said crank, the segment teeth meshing with the driving pinion, means for driving said loosely mounted pinion and means for connecting and disconnecting the crank and the spur gear while the latter is in operation.

12. In gearing of the class described, a fixed support provided with a rotatable driving shaft, a stub shaft, an intermediate shaft and a controlling lever, combined with a driving pinion fixedly mounted on the driving shaft, a sheave loosely mounted on the driving shaft, means for rotating the sheave, a spur pinion attached to and rotatable with said sheave, a spur gear rotatably mounted upon the stub shaft, a gear and a pinion mounted on the intermediate shaft and meshing with the spur pinion and

lowered position, and also with means for limiting its upward movement.

10. The combination with a fixed support and a driving shaft rotatably mounted thereon, of a pinion loosely mounted upon said shaft, a pinion fixedly mounted on the shaft to rotate therewith, a stub shaft mounted on the support, a spur gear revolvably mounted upon the stub shaft, gearing connecting said spur gear with the loosely mounted pinion, means for actuating the latter, a crank associated with said spur gear, a pivoted toothed segment in mesh with the pinion fixed on the driving shaft, said segment being operatively connected with said crank, a shoulder on the crank, a detent on the spur gear adapted to engage said shoulder, and means for controlling said detent, said controlling means including a pivoted manually operated lever having two cams the engaging surfaces of which are oppositely inclined, said cams being adapted to be alternately brought into the path of the moving detent by said lever to raise or depress the latter as desired, said detent comprising a vertically movable arm horizontally pivoted to lugs on the spur wheel and frictional means mounted in the detent to cooperate with the rim of the said gear.

11. Gearing of the class described comprising in combination with a fixed support, a stub shaft mounted thereon, a rotatable driving shaft mounted therein and a shaft intermediate the latter and the stub shaft, of a driving pinion fixed on the driving shaft to rotate the same, a spur pinion loosely mounted to rotate about said driving shaft, a spur gear mounted to rotate said stub shaft, a spur gear and a pinion mounted upon the intermediate shaft and meshing respectively with the loosely mounted pinion and the spur gear, a link loosely mounted at one end upon the driving shaft, a crank loosely mounted at one end upon the stub shaft, a toothed gear segment pivotally connected to the free ends of said link and of said crank, the segment teeth meshing with the driving pinion, means for driving said loosely mounted pinion and means for connecting and disconnecting the crank and the spur gear while the latter is in operation.

12. In gearing of the class described, a fixed support provided with a rotatable driving shaft, a stub shaft, an intermediate shaft and a controlling lever, combined with a driving pinion fixedly mounted on the driving shaft, a sheave loosely mounted on the driving shaft, means for rotating the sheave, a spur pinion attached to and rotatable with said sheave, a spur gear rotatably mounted upon the stub shaft, a gear and a pinion mounted on the intermediate shaft and meshing with the spur pinion and

spur gear respectively, a crank loosely mounted on the hub of said spur, a segmental gear meshing with the driving pinion, links loosely mounted on the driving shaft, 5 one on each side of the segmental gear, and pivotally connected thereto, an arm on the segmental gear pivotally connected with the crank, a shoulder on the crank, a detent on the spur gear adapted for engagement with 10 said shoulder and means on the controlling lever for engaging and disengaging the detent and shoulder, whereby said spur gear

will function either as a transmission gear to rotate the driving shaft or as a driving gear when the driving shaft is not rotating.

In testimony that I claim the foregoing as my invention I affix my signature, in the presence of two witnesses, this — day of

15

, 1921.
